UNITED STATES PATENT OFFICE.

ALEXANDER BERNHARD DRÄGER, HANS WILHELM CHRISTIAN SCHRÖDER, AND ERNST WILHELM KUNZMANN, OF LUBECK, GERMANY; SAID SCHRÖDER AND SAID KUNZMANN ASSIGNORS TO SAID DRÄGER.

BURNER FOR THE AUTOGENOUS CUTTING OF METALS.

Application filed August 18, 1921. Serial No. 493,413.

To all whom it may concern:

Be it known that we, ALEXANDER BERNHARD DRÄGER, HANS WILHELM CHRISTIAN SCHRÖDER, and ERNST WILHELM KUNZMANN, German citizens, residing at Lubeck, Germany, have invented certain new and useful Improvements in Burners for the Autogenous Cutting of Metals (for which we have filed applications in Germany, June 10 2, 1920, and June 19, 1920), of which the following is a specification.

The present invention relates to burners for the autogenous cutting of metals.

In hitherto known burners with a central oxygen cutting-jet and an annular concentric space for a heating flame, the inner oxygen cutting-nozzle is screwed into the oxygen supply bore of the burner head, and the outer heating nozzle is likewise screwed into the burner head and forms around the inner nozzle the annular passage for the heating gas. It has however been found that in this arrangement, in consequence of unavoidable errors in manufacture in all 25 parts, and frequently through wear, no exactly concentric position of the nozzles, and consequently no uniform annular outlet opening or slit for the heating flame, can be obtained. The heating flame must however, 30 in order to produce a good cut all around and not flash back into the burner at the slightest resistance, always issue from an annular passage of perfectly uniform width and concentricity.

According to this invention this requirement is complied with by the special method of construction of the nozzles. The small errors in manufacture are no longer capable of influencing the concentric position 40 of the nozzles, and any wearing of the nozzles and burner heads is not detrimental to the correct action of the burner.

The packing of a nozzle with two separate bores as gas conduits also offers considerable difficulty. Only when this question is satisfactorily solved can such a nozzle arrangement be used at all. Before all things it must be taken into consideration that a large number of nozzles must fit one 50 burner head. The fitting of such nozzles to the burner head by grinding and the like is therefore impossible. Furthermore packing rings of the usual materials, such as vulcanized fibre, pasteboard, leather, rub-

ber and the like, cannot be used, as the heating thereof has to be reckoned with.

According to this invention an efficient packing is secured between the body of the nozzle and the separate supply pipes for the oxygen and the heating gas in the body 60 of the burner, by the aid of two concentric crater or tapered packing rings, which are provided either on the inner end face of the nozzle and act as a packing against a surface turned flat at the base of the recess turned in the head of the burner, or conversely, are provided at the base of the recess turned in the head of the burner and act against the end face of the nozzle which is ground off level.

A further feature of the invention resides in the special construction of the collecting chamber and annular outlet slit for the heating gas situated between the oxygen nozzle with its outlet union, and the cap 70 of the mouthpiece or heating jet, the apparatus being so constructed that these two chambers through which the mixed gas passes are of the same, or approximately 75 the same, cross sectional area over the whole 80 of the course traversed by the gas, and that the length of the annular passage is definitely proportional to the velocity of the flow of the gas and to the retrograde absorption of heat by the nozzles, in order to 85 still more efficiently prevent the striking back of the heating flame in the burner.

Finally, according to this invention, that part which, in ordinary use of the burner, is next the cap of the mouthpiece and is 90 mostly subjected to wear or destruction through careless handling, that is the outlet tip of the oxygen nozzle, can be made as a separate part and inserted interchangeably and gas tight in the oxygen nozzle. In case 95 of any damage, which only extends to this outlet tip, this latter then only needs to be interchanged.

Several constructional examples of the invention are illustrated in the accompanying 100 drawings.

Figure 1 is a general side elevation of the new cutting burner.

Figure 2 is a longitudinal section of the burner head on a larger scale.

Figure 3 is a similar longitudinal section through a burner head of somewhat different constructional form as regards the packing

between the oxygen or cutting nozzle and the head of the burner.

Figure 4 shows in a similar sectional view another construction of a packing between the nozzle and the head of the burner.

Figure 5 is a longitudinal section through a modified constructional form of the head of the burner in which the course traversed by the heating gas through the collecting 10 chamber and annular outlet slit between the two nozzles is of the same cross sectional area.

Figure 6 is a similar sectional view through a burner head of somewhat different 15 constructional form.

Figure 7 shows likewise in longitudinal section a burner head, in which however the outlet tip of the oxygen nozzle is interchangeable, the heating nozzle being screwed on to 20 an external screw thread on the oxygen nozzle.

Figure 8 shows a similar burner head with an interchangeable outlet nozzle, in which however the preliminary heating nozzle 25 is screwed into an internal screw thread in the oxygen nozzle.

Similar letters of reference refer to similar parts throughout the several figures.

From the burner handle *a*, lead two pipes 30 *b* and *c* (Figure 1) constituting respectively oxygen and heating gas supply pipes to the burner head *d* which is provided with an inner nozzle *e* and an outer nozzle-cap or mouth-piece *h*. The concentric bore *f* 35 (see Figures 2 and 3) of the burner head *d* supplies the oxygen, and the eccentric bore *g* supplies the heating gas. In the inner nozzle *e* are provided separate bores or passages, the central one *i* being for the oxygen 40 and the others *k* which surround it, for the heating gas. The lower or end portion of the nozzle *e* is shouldered to form a projecting central nozzle-tip *l* traversed by a concentric bore which is coaxial and communicates with the oxygen passage *i*. This nozzle-tip *l* forms the oxygen outlet proper. The shouldered end portion of the nozzle 45 *e* is provided with an external screw thread, on to which is screwed the nozzle-cap *h* which has a central opening or hole in it which is slipped over the nozzle-tip *l*. In its final position this cap or mouth piece is spaced from the nozzle *e* to provide a chamber *m* in which the heating gas is collected 50 and from which it is conveyed, and to convey it into the annular slit between the nozzle-tip *l* and the wall of the central opening in the cap, the diameter of which opening is obviously slightly greater than that of the 55 nozzle-tip *l*. It will be readily seen that with this arrangement the centering of the nozzle and nozzle-tip *e*, *l* and the cap *h* is effected in a simple and efficient manner. For accurate adjustment it is only necessary 60 that the nozzle-tip *l* and the central 65

opening of the cap *h* be coaxial with the screw-joint between the cap *h* and the nozzle-body *e*, that is to say, with the female and male threads of this screw-joint.

Formerly in the hitherto known burners 70 the socket of a separate inner nozzle and the opening of an outer nozzle had to run coaxially with two screw-joints, one connecting the inner nozzle and the other the outer nozzle with the nozzle-body. 75

As the nozzle and nozzle-tip *e*, *l* and the cap *h* are not separated from each other when once screwed up, but are interchanged as a whole, no wear of the threads and the surfaces takes place, which effect the centering. Permanently uniformly working nozzles are therefore obtained and much time is saved when interchanging the nozzles for cutting work-pieces of different thicknesses. 80

The methods of packing shown in Figures 85 2 and 3 have proved to be suitable for the purpose and practicable. Figure 2 shows an elevated flat surface *d*¹ at the base of the recess in the burner head *d* and two concentric tapered rings *n* and *o* preferably 90 lying in the same plane on the inner end face of the nozzle body *e*, *l*. The inner ring *n* forms a packing or tightening means which prevents the oxygen from leaking outwards in a radial direction, whilst the outer ring *o* completes the annular space for the heating gas which therefore has access only to the bores *k* and cannot leak outwards past the upper connecting screw-threads. 95 In order to protect the tapered rings when the nozzle *e* is unscrewed, a protecting ledge or border *p* is provided outside the outer ring *o*. The second method of packing which can as well be used, is shown in Figure 3. In this case, only one tapered ring 100 *n* is used to pack the oxygen conduit, while the packing for the heating gas, which is under low pressure, is formed by an asbestos packing ring *q* and a gland-nut *r*. The packing ring *q* is pressed by the nut *r* 105 against the burner head *d* and against the external screw-thread of the nozzle *e*. 110

The present invention renders the manipulation of the new burner considerably more simple in comparison with the known burners with two interchangeable nozzles. Furthermore the nozzles cannot be wrongly interchanged with each other as in the case of well known burners with two interchangeable nozzles, which when used the wrong 115 way round may under some circumstances result in an accumulation of the heating gas and in the case of using a gas consisting of a mixture of oxygen and a heating gas, a passing back of the oxygen into the heating 120 gas conduit. The principal advantage of this invention is however that the centering of the nozzles is easily obtained and ensured, and is not subjected to any change. 125

In the constructional form shown in Fig- 130

ure 4 the tapered rings n^1 o^1 are mounted on the burner head d , while the flat surface e^2 is provided on the nozzle e^1 . It is however necessary and also usual, for the burner head, which carries the tapered rings, to consist of a hard metal and the nozzle of a softer metal such as copper for example. By this means it is ensured that the form of the tapered packing rings is maintained, while they become pressed into the soft material of the nozzle when the latter is screwed in and tightened up. An absolutely satisfactory packing between metal and metal is rendered particularly possible by slightly deforming one of the two packing surfaces. The inner ring n^1 , which is of a smaller diameter, can force itself more easily into the mouthpiece e^1 when the latter is tightened up than the external ring o^1 of larger diameter. In consequence thereof it is convenient to make the inner ring n^1 project slightly beyond the outer ring o^1 and therefore touch the mouthpiece first when screwed in. (This arrangement of the rings is shown in Figure 4). The inner ring n^1 , after the nozzle e^1 has been completely tightened up, will provide a larger packing surface at the nozzle than the outer ring o^1 , which is advantageous because the central oxygen is under a higher pressure than the heating gas.

It is of special advantage in the manufacture of the apparatus that the tapered packing rings are contained in the burner and that the mouthpiece is provided with a flat surface e^2 , as the production and testing of an accurate external flat surface offers no difficulty. The case is however different when the arrangement of flat surface and pointed rings is reversed. The latter are also better protected against damage when situated in the head of the burner than they are when provided on the mouth-piece.

Should any damage happen to the flat surface e^2 of the mouthpiece, this surface can be ground down on a flat emery wheel or the like and thereby again made fit for use.

It will be easily seen that a simultaneous packing of several passages in the manner described is attained in a more perfect manner taking into consideration the usual material, the ease of production, the interchangeability and the upkeep. A reliable packing between the head of the burner and the mouthpiece is however an absolute necessity for the proper and safe working of the burner.

When using mixed gas as the heating gas, the disadvantage has been experienced, that when the burner becomes highly heated after cutting periods of long duration or when showers of sparks are produced, or when low external resistance occurs in the

burner, the heating flame strikes back to the mixing point and destroys the internal parts.

According to the present invention this disadvantage can be obviated by the special construction of the collecting chamber m (see Figures 1 and 2) and of the annular outlet slit between the nozzle-tip l of the nozzle and the cap or mouthpiece h . Figures 5 and 6 show two constructional examples of burners with such improved passages for the passage of the mixed gas. The nozzle e , h may in this case be screwed into the head d of the burner separately, as is shown in Figure 5, or the outer nozzle h can be screwed as a cap on to the inner nozzle e (see Figure 6). In both constructional forms a collecting chamber m^1 for the mixed gas and an annular outlet passage h^1 is formed in the front part between both nozzles.

In the known burners, which are not so constructed the mixed gas flame burns quietly in front of the annular passage as long as the speed at which it issues is so high and the temperature of the issuing mixed gas is so low that the burner zone forms an outwardly directed conical ring. When however owing to uncertain guiding of the burner, fused metal, or an excess of pressure produced by the cutting oxygen a resistance is formed in front of the nozzles, or when excessive heating of the nozzles takes place owing to reflex radiation particularly when piercing holes, the burner zone runs back into the annular passage. Striking back also takes place by the action of flying sparks which get into the annular passage. It is then said that the speed of ignition exceeds the speed of issue or flow. If therefore the conditions are favourable to the flame to continue burning in the burner in such a way that the path of the supply of the mixed gases becomes reduced from a wider cross sectional area to a narrower one by degrees up to the point of issue, or immediately in front of it, that is to say the speed of flow decreases in a back-ward direction, the flame runs back to the mixing point of the gases and can then only be put out by shutting off the valves. On the basis of this knowledge therefore the annular passage h^1 and the adjoining collecting chamber m^1 are so constructed in the subject matter of the invention, that the speed of flow is sufficient at this point to prevent the running back of the flame into the wider supply passages k or k^1 (or the grooves) in the nozzles and head of the burner. It is necessary for this purpose to make the annular passage h^1 or the nozzle-tip l and the bore of the nozzle h of such a length that the outer excess pressure set up as the resistance does not affect or have any appreciable effect, upon the kinetic energy of flow.

This fixed minimum is in relationship to the speed of flow, or the proportion between the volume of flow and cross sectional area.

A similar dependence exists between the 5 length of the annular passage and the degree of heating which the nozzles are subjected in the treatment of pieces of work.

The points of the nozzles become very hot but farther backwards the temperature is 10 kept down by the gas as it flows in. It is therefore important to allow the high speed of flow to commence at a point where no heating up which would favour a backfire could possibly take place.

With great speed 15 of flow and in burners for materials of slight thickness the passage h^1 may be shorter than is permissible in burners for thicker materials and internal work, which use only a low pressure of mixed gas and

therefore a low speed of flow, and are subjected to excessive heating. Backfires due to excessive pressure, sparks which may have been blown in, or heating, always extend only into the front part of the annular 20 passage and immediately after the cessation of the cause, which only arises temporarily, the flame again burns normally in front of the nozzles without being capable of damaging them in any way whatsoever.

30 The novelty of the constructional examples shown in Figures 7 and 8 consist in making the oxygen or cutting nozzle in two parts, namely the nozzle part e separated from the pipe f (oxygen) and g (heating or combustible gas) in the burner head d by tapered packing rings n and o and the nozzle-tip l^1 or l^2 . This latter can be inserted gas tight in the part e by being screwed in, forced in or in any other suitable manner, so that in case of necessity it can be easily interchanged. This interchangeability of the nozzle-tip l^1 or l^2 constitutes the great advantage compared with the oxygen nozzles with fixed sockets (see 40 Figures 2, 3 and 5, 6).

45 The centering of the parts e and l or l^2 , once carried out when replacing or repairing them for the purpose of providing an accurate annular opening between the part e and the cap h , remains constant during the use of the burner as it is always only the mouthpiece, consisting of the parts e , l^1 , h or e , l^2 , h , which is interchanged as a whole for cutting the different thicknesses of material.

50 It is universally known that the mouthpieces of burners which are subjected to the action of showers of sparks and the striking back of the heating flame must be made of copper. The construction of the mouthpiece in three parts according to Figures 7 and 8, therefore offers in comparison with the construction thereof in two parts according to Figures 2, 3, 5 and 6 the improvement that the screw portion e which is less subjected

to the action of the flame, can be made of a metal which is cheaper, harder and easier to work, such for example as brass. The increased hardness means greater durability 70 against the mechanical strain produced by the spanner when interchanging the mouthpieces.

Between the constructional forms according to Figures 7 and 8 there are only differences of an economical kind.

75 In the first case according to Figure 7 a smaller nozzle-tip l^1 is necessary, but an increased amount of work when boring the longer screw portion e . In the second case according to Figure 8 the contrary is the 80 case, i. e. a larger nozzle-tip l^2 and shorter screw portion e .

We claim:

1. In a burner for the autogenous cutting of metals with a central oxygen cutting jet 85 and an annular concentric heating flame, the combination of a burner head, a nozzle detachably connected therewith and provided with a concentric oxygen passage and a passage for a heating gas, means on said 90 nozzle co-operating with said head to provide a packing whereby said oxygen and gas passages are sealed against communication with each other at this point, a nozzle-tip 95 carried by said nozzle and constituting an outlet for the oxygen and a nozzle-cap carried by said nozzle and forming therewith a gas collecting chamber communicating with said gas passage, said nozzle-cap being provided with a central opening through 100 which said nozzle-tip projects and of larger diameter than said nozzle-tip to form therewith an annular outlet slit for said heating gas.

2. In a burner for the autogenous cutting 105 of metals with a central oxygen cutting jet and an annular concentric heating flame, the combination of a burner head, a nozzle detachably connected therewith and provided with a concentric oxygen passage and a 110 passage for a heating gas, concentric tapering rings located between said burner head and nozzle and comprising an integral part of one of said elements in engagement with the other of said elements to provide a packing whereby said oxygen and gas passages are sealed against communication with each other at this point, a nozzle-tip carried by 115 said nozzle and constituting an outlet for the oxygen and a nozzle-cap carried by said nozzle and forming therewith a gas collecting chamber communicating with said gas passage, said nozzle-cap being provided with a central opening through which said nozzle-tip projects and of larger diameter 120 than said nozzle-tip to form therewith an annular outlet slit for said heating gas.

3. In a burner for the autogenous cutting 125 of metals with a central oxygen cutting jet and an annular concentric heating flame, 130

the combination of a burner head, a nozzle detachably connected therewith and provided with a concentric oxygen passage and a passage for a heating gas, said nozzle 5 having a flat inner end surface, concentric tapering rings comprising an integral part of said burner head and engaging said flat surface of the nozzle to comprise a packing whereby said oxygen and gas passages are sealed against communication with each other at this point, a nozzle-tip carried by said nozzle and constituting an outlet for the oxygen and a nozzle-cap carried by said nozzle and forming therewith a gas collecting 10 chamber communicating with said gas passage, said nozzle-cap being provided with a central opening through which said nozzle-tip projects and of larger diameter than said nozzle-tip to form therewith an annular outlet slit for said heating gas.

4. In a burner for the autogenous cutting of metals with a central oxygen cutting jet and an annular concentric heating flame, the combination of a burner head, a nozzle 15 detachably connected therewith and provided with a concentric oxygen passage and a passage for a heating gas, said nozzle having a flat inner end surface, concentric tapering rings comprising an integral part 20 of said burner head and engaging said flat surface of the nozzle to comprise a packing whereby said oxygen and gas passages are sealed against communication with each other at this point, said inner ring projecting slightly beyond the outer ring and 25 engaging said end surface in advance of the outer ring as the parts are assembled, a nozzle-tip carried by said nozzle and constituting an outlet for the oxygen and a 30 nozzle-cap carried by said nozzle and forming therewith a gas collecting chamber communicating with said gas passage, said nozzle-cap being provided with a central opening through which said nozzle-tip projects and of larger 35 diameter than said nozzle-tip to form therewith an annular outlet slit for said heating gas.

5. In a burner for the autogenous cutting of metals with a central oxygen cutting jet and an annular concentric heating flame, the combination of a burner head, a nozzle 40 detachably connected therewith and provided with a concentric oxygen passage and 45

a passage for a heating gas, means on said nozzle co-operating with said head to provide a packing whereby said oxygen and gas passages are sealed against communication with each other at this point, a nozzle-tip carried by said nozzle and constituting an outlet for the oxygen and a nozzle-cap carried by said nozzle and forming therewith a gas collecting chamber communicating with said gas passage, said nozzle-cap being provided with a central opening through which said nozzle-tip projects and of larger 50 diameter than said nozzle-tip to form therewith an annular outlet slit for said heating gas, said collecting chamber and outlet slit for the heating gas being of approximately the same cross-sectional area over the whole 55 of the path traversed by the gas and the length of the annular slit being definitely proportioned to the speed of flow and the reflex absorption of the heat by the nozzles for the purpose of preventing the striking 60 back of the preliminary heating flame into the burner.

6. In a burner for the autogenous cutting of metals with a central oxygen cutting jet and an annular concentric heating flame, the combination of a burner head, a nozzle 65 detachably connected therewith and provided with a concentric oxygen passage and a passage for a heating gas, means on said nozzle co-operating with said head to provide a 70 packing whereby said oxygen and gas passages are sealed against communication with each other at this point, a nozzle-tip comprising a separate element detachably connected with said nozzle and constituting an outlet for the oxygen and a nozzle-cap carried by said nozzle and forming therewith a gas collecting chamber communicating with said gas passage, said nozzle-cap being provided with a central opening through 75 which said nozzle-tip projects and of larger diameter than said nozzle-tip to form therewith an annular outlet slit for said heating gas.
